PORTABLE COTTON COMPRESS AND
REBANDER

Walter Crump, Walsenburg, Colo.

Application September 20, 1934, Serial No. 744,791

5 Claims. (Cl. 100—9)

My invention relates to a novel and improved cotton or hay press and rebander and has especial reference to one which is portable so that it can be readily moved in a truck from one 5 warehouse to another.

The invention also contemplates a device of this kind which is simple and durable in construction, easy to operate, and which includes a novel cable incorporating actuating means comprehending a floating cable-supported guide frame and means actuated by the cable for effecting actuation of the press.

Additionally, the invention contemplates a press for cotton or other material which incorporates a cable-operated toggle actuating means.

Other objects and advantages will become apparent as the description proceeds, reference being had to the accompanying drawings illustrating a now preferred example of the invention, which, however, may be considerably changed and modified within the spirit and scope of the appended claims.

In the drawings,

Figure 1 is a side elevation of a press embodying my invention.

Figure 2 is a sectional view taken on line 2—2 of Fig. 1 of the press without the bale.

Figure 3 is an end elevational view.

Figure 4 is a central vertical sectional view.

Referring specially to the drawings, wherein the same reference characters have been used to designate the same parts in all views, letter A designates a platform or base member supported by wheels B. Mounted upon platform A is an upstanding fixed frame comprehending preferably angle iron corner posts 5, top cross members 5a, 5b, the brace members 5c extending from posts 5 for reinforcing the medial portions of top cross 5a which carry the bearings 7 for the shaft 8 of the pulleys 9. The fixed frame also has the side bars 5d connecting the posts 5 intermediate their ends, as shown in Fig. 1. Furthermore, as shown in Figure 4, the inner ends of the bearings 7 are supported by the vertical posts 10 carried by the cross member 10b extending between intermediate side bars 5d, as shown in dotted lines in Fig. 1. Posts 10 also have the vertical slots 10a, as shown, the purpose of which will be shortly explained.

Working within the fixed frame and guided by the angle iron corner posts 5 thereof, as best shown in Fig. 2, is a slidable frame comprehending the upstanding preferably angle iron corner posts 6, upper and lower side members 6b and 6a, respectively, and the intermediate bars 6c connecting corner posts 6.

The slidable frame also has the vertical slat members 18 connecting members 6b, 6c at each side; and also the swingable gate-like slat members 16 pivotally carried as at 16a by interme-

diate bars 6c and adapted to be secured by pins 17 in slots 15a in the outer ends of the preferably channel-form compressor head cross bars which are disposed across the lower side members 6a, as best shown in Figures 1 and 2. 5

It should here be noted that the fixed frame 5, 5a, etc. has the short channel form compressor head cross bars 14 connecting the intermediate side bars 5d, as shown in Figs. 1, 3, and 4. The space between the bars 14, 15 of the 10 fixed and movable frames, respectively, is the bale chamber and the bale, such as 25 therein, is adapted to be compressed by the upward actuation of the sliding frame 6, 6a, etc., which causes the compressor head bars 15 to compress 15 the bale against the compressor head bars 14.

The means whereby the sliding frame 6, 6a, etc. is actuated will now be described.

Figures 1, 3, and 4 disclose the vertical bars 11 depending from the medial portion of each upper 20 side member 6b of the movable frame 6, 6a, etc.; and also that the lower ends of such vertical bars 11 carry the shaft 12 having the spaced pulleys 13. Figures 3 and 4 show that the end portions 15 of shaft 12 extend through the slots 10a in the 25 vertical posts 10 of the fixed frame 5, 5a, etc., to be thereby guided and sustained in the vertical movements of slidable frame 6, 6a, etc.

Toggles comprising side arms 19, 19, and 20, 20, connected by reinforcing frames 19a, 20a (Figs. 30 3 and 4) are arranged in pairs 19, 20 and 19, 20, as shown with their inner ends connected by shafts 23, 23a respectively, having the laterally spaced pulleys 24, 24a, respectively. The outer ends of arms 19 are pivotally connected to the 35 upper side members 6b of the slidable frame, as shown at 22 in Figure 1; and the outer ends of the arms 20 are pivotally secured as at 21 to the intermediate side bars 5d of the fixed frame. Thus, when the pulley-carrying shafts 23, 23a 40 which connect the pairs of arms 19, 20 and 19, 20 are actuated inwardly, the pivot points 22, 21 (Fig. 1) tend to separate with the result that sliding frame 6, 6a, etc. will be actuated upwardly 45 to compress the bale of hay, cotton, or the like 25 between the heads provided by the channel-form cross bars 14, 15.

In order to actuate the pivots 23, 23a inwardly toward one another as aforesaid, I provide the cable 29 having one end wound on the drum 27 50 which is secured on base A and has the geared or other driving connection 28 with the motor 26, which is also secured to the base A.

Cable 29 passes from drum 27 over pulley 30 whose shaft 30a is carried by bearings 31 intermediate the ends of the corner posts 5 of the fixed frame 5, 5a, etc. 55

From pulley 30 cable 29 divides into two branches which pass under the respective pulleys 13 of the depending bars 11 of the movable frame 60

and which pulleys 13 have their shaft 12 guided in slot 10a of posts 10, as already mentioned.

After passing around the lower parts of pulleys 13, the branches of cable 29 lead upwardly (Figs. 5 1 and 4) about the inner portions of the laterally spaced pulleys 33 of a floating frame 32 which is entirely supported by the branches of cable 29, as will be presently apparent.

The branches of cable 29 pass over the pulleys 10 33 and outwardly to the spaced pulleys 24 of the toggle arms 19, 20 at the right (Fig. 1) passing about said pulleys 24 and then back and under the spaced companion pulleys 34 of said floating cable-supported frame 32. From thence the cable 15 branches lead upwardly and over the spaced pulleys 9 carried by the members 5a, 10, 7, 8 of the fixed frame 5, 5a, etc., as shown in Figs. 1, 3, and 4.

From pulleys 9, the branches of cable 29 pass 20 downwardly and under the upper pulleys 35 of the floating frame 32. From pulleys 35 cable branches 29 pass outwardly to be trained about the spaced pulleys 24a of the left hand toggle arms 19, 20 (Fig. 1) whence they are brought inwardly to floating frame 32 which provides the spaced pulleys 36 over which said branches of cable 29 are trained and finally lead downwardly and are appropriately secured to the floating frame.

30 The operation may be briefly summarized as follows:—

The bale 25 to be compressed having been inserted into the bale chamber space between the compressing heads 14, 15, the gate bars 16 are 35 let down and locked in place by pins 17, whereupon the motor 26 is started causing cable 29 to be wound onto drum 27. This causes the intermediate toggle pivots 23, 23a to be pulled toward one another. Since the outer ends of toggle arms 40 20 are pivoted to 5d which is a part of fixed frame 5, 5a, etc., the sliding frame 6, 6a, etc. will be lifted and the bale 25 compressed between the head 14, 15 of the fixed and movable frames respectively. The pull of the cable on pulleys 9 is 45 amply sustained by 5a, 5c, 5 and by posts 10; and the slot 10a of post 10 sustains the shaft 12 of pulleys 13 (Figs. 1 and 4) which, of course slides up and down with frame 5, 5a, etc.

By making the compressor head cross bars 14, 50 15 of channel form the passing of bale wires under and over the bale 25 is greatly facilitated as such bars guide the wires.

I claim:

1. A press comprising in combination, a fixed 55 frame and a sliding frame working in said fixed frame, said frames having cooperating compressing heads, opposed toggles extending outwardly at opposite sides of said frames and connecting the same, a single cable secured to said sliding frame, a cable guide element on said fixed frame above the sliding frame and over which the cable is trained, cable guides at the pivots connecting the arms of each of said toggles and over which intermediate portions of said cables are trained, a floating frame within said sliding frame between said toggles and providing cable guide portions for the intermediate portions of said cable leading to and from the guide means of said toggle pivots, one end portion of said cable leading from 60 a guide portion of said floating frame to its point of attachment to said sliding frame, a cable guide member carried by said sliding frame and to which the other end portion of the cable leads 65

from another guide portion of said floating frame in its passage to an operating means, a support for said cable guide element of said fixed frame and providing a guide for the cable guide member of said sliding frame. 5

2. A press comprising in combination a fixed frame and a sliding frame working in said fixed frame, said frames having cooperating compressing heads, opposed toggles extending outwardly at opposite sides of said frames and connecting the same, a single cable secured to said sliding frame, a cable guide element on said fixed frame above the sliding frame and over which the cable is trained, cable guides at the pivots connecting the arms of each of said toggles and over which intermediate portions of said cables are trained, a floating frame within said sliding frame between said toggles and providing cable guide portions for the intermediate portions of said cable leading to and from the guide means of said toggle pivots, one end portion of said cable leading from a guide portion of said floating frame to its point of attachment to said sliding frame, and a cable guide member carried by said sliding frame and to which the other end portion of the cable leads 20 25 from another guide portion of said floating frame in its passage to an operating means.

3. In a press, a sliding frame providing a bale chamber, a bale compressing head carried by said frame and providing one end of said bale chamber, 30 said head comprising laterally spaced cross members, a support for said sliding frame, a fixed head carried by said support and disposed within said bale chamber in cooperative relationship with said head of the sliding frame, a gate closing a side of said bale chamber, outwardly disposed gate carrying pivot means on said sliding frame parallel with said heads and disposing said gate outwardly of said support, said cross members of said first-mentioned head extending outwardly of said support, and gate securing portions formed at the ends of said cross members. 35 40

4. In a press, a stationary frame, a movable frame slideable thereon, a fixed bale compressor head on said fixed frame, a bale compressor head on said slideable frame and movable therewith, a toggle connecting said fixed and movable frames, shafts comprising pivots for the break joints of the toggle, pulleys journaled on said shafts, a pulley mounted at a fixed point on the fixed frame, a pulley mounted at a fixed point on the movable frame, a winding drum associated with the fixed frame, a cable trained over all said pulleys and winding drum, and means for operating said winding drum to reel in said cable and thereby actuate the toggle to move said movable frame on the fixed frame. 45 50 55

5. In a press, a fixed frame, a movable frame slideable thereon entirely within the confines thereof, a toggle lever connecting said frames, 60 cooperative bale presser means on said frames, a floating frame between said fixed and movable frames, cable guide pulleys carried by said floating frame, cable guide pulleys journaled at the break joints of the toggle, cable guide pulleys disposed at fixed points in said fixed and movable frames, a winding drum associated with the fixed frame, a cable trained over all said pulleys and drum, and means for operating said drum to wind in said cable and thereby actuate said toggle 65 70 lever to effect relative movement between all said frames.

WALTER CRUMP.
